(57) **CLAIM**

The ornamental design for a beverage vending machine, as shown and described.

DESCRIPTION

FIG. 1 is a front right perspective view of a beverage vending machine, according to a first embodiment;

FIG. 2 is a rear right perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a front right perspective view of a beverage vending machine, according to a second embodiment;

FIG. 9 is a rear right perspective view thereof;

FIG. 10 is a front elevational view thereof;

FIG. 11 is a right side elevational view thereof;

FIG. 12 is a left side elevational view thereof;

FIG. 13 is a rear elevational view thereof; and,

FIG. 14 is a top plan view thereof.

The broken lines in the drawings depict portions of the beverage vending machine that form no part of the claimed design.
